United States Patent Office.

G. W. LOY, OF NACOGDOCHES, TEXAS.

Letters Patent No. 100,537, dated March 8, 1870.

IMPROVED MILL-STONE DRESS.

The Schedule referred to in these Letters Patent and making part of the same.

To all whom it may concern:

Be it known that I, G. W. Loy, of Nacogdoches, in the county of Nacogdoches, and State of Texas, have invented a new and improved Mill-Stone Dress; and I do hereby declare that the following is a full, clear, and exact description thereof, which will enable those skilled in the art to make and use the same, reference being had to the accompanying drawings forming part of this specification.

My invention relates to that class of grain-mills wherein the stones are provided with converging furrows, and consists in an improvement upon the present mode of dressing the stones, as will be more particularly specified hereinafter.

Figure 1 represents a plan view of the bed-stone, showing the elbow-shape of the furrows.

Figure 2 represents a plan view of the face of the upper stone.

A represents the stationary stone, with the elbow-dress divided into sections, which are modified in respect to the lands and small furrows, and numbered on the edge opposite the center of each section.

Nos. 1 and 2 represent the dress for small mills for grinding corn, from twelve to twenty inches in diameter, with main elbow-furrows *c* and solid sections, the lands or sections being cut up into straw-furrows *c'*.

No. 3 also represents the dress for a corn-mill, but of large size, with an intersecting elbow-furrow *D*, the lands being also cut up into straw-furrows.

No. 4 represents a dress for a still larger mill, with two intersecting furrows *D*, the lands cut up into small furrows designed for grinding wheat. This might be called an inclined face.

The small furrows *d* in the lands are cut very shallow, with a small space between them, which makes the face of the stone nearly all furrow. This, as demonstrated by practical experiment, answers an excellent purpose.

Nos. 5 and 6 represent a different dress for wheat. In making a fine article of flour it may be necessary to omit every other small furrow in the lands having a solid space between them, as here represented.

h h represent the solid spaces between the furrows.

The advantage gained by the elbow-dress on the stationary stone is that the grain passes more freely in at the eye to the elbow, where the speed is increased.

The straight part of the dress, from the elbow out, inclines back from the way the stone runs, and serves

to retain the grain until it is ground, where the greatest speed is given.

The furrows marked 7 7 show the angle of the furrows in the bed-stone, which I prefer where the bottom stone runs. When the bottom stone runs, I angle the furrows about three inches back from a straight line drawn from the center, (see section No. 1.)

8 8 represent the angle in the stationary stone when the top stone runs.

The reason why I make this difference in the angles when the bottom stone runs is that, the furrow in the stationary stone being bottom upwards, the meal will fall on the runner and be discharged. It also prevents the grain from passing out along the furrow, causing it to be ground by centrifugal force.

The reason why the furrows in figs. 8 8 should incline more the way the mill runs, is because they would fill up and choke if they angled back like figs. 7 7, for when the latter angle is used the meal is accelerated by the centrifugal force imparted by the bed, which is greater than when the upper stone runs.

I do not confine myself to any particular angle, but claim the right of varying the angles to suit the different kind of mills; neither do I confine myself to any specified number of furrows, but I claim the right of varying to suit the different sized mills with the curve and elbow-dress. I propose to use the curve and elbow-dress both on the same mill.

Fig. 2 represents the runner with the curve-dress, the same letters and figures representing the main furrows, land, and intersecting furrows as in fig. 1. It also shows the different dresses for wheat and corn for the different-sized mills.

The curve dress on the runner has the advantage of distributing the grain more equally throughout the rock than any dress known to me.

Having thus described my invention,

What I claim as new, and desire to secure by Letters Patent, is—

A stationary stone, having the elbow-dress to force the grain out to the points of greater speed, and the straight dress to retain the grain at the point of greatest speed until ground, as shown in fig. 1 of drawing, in combination with a runner having a curved dress, all as shown and described.

G. W. LOY.
